2,602,992

COMBINATION STRAIGHT AND SAFETY RAZOR

Claire Jack Elliott, Richmond, Va.

Application January 28, 1947, Serial No. 724,739

2 Claims. (Cl. 30—69)

1

This invention relates to razors and cutting implements of the safety razor type, and in particular includes a handle, a blade holder and a guard, wherein single or double edge blades may be readily attached to the end of the handle with the blade positioned perpendicular to the axis of the handle, or aligned therewith.

Although razor blades are distributed universally through numbers of merchandising channels, there are times when it is not convenient, and sometimes impossible, to obtain the desired type of blades.

With this thought in mind, the invention contemplates a combination of elements which comprises a safety razor in which either a single or double edge blade may be used, and in which the blade may be held for shaving or cutting either perpendicular to the axis of the handle, or extending straight outward from the end thereof.

The purpose of this invention is to provide a safety razor in which either a single or double edge blade may be used and which may be used for shaving, cutting, scraping, or stropping or honing.

Substantially every one is at some time confronted with the necessity of using a safety razor blade as a knife, and for this reason, the combination safety razor of this invention includes means for holding the blade for shaving, and the parts are also constructed wherein they may be turned to hold the blade lengthwise of the handle, so that it may be used as a knife.

The object of the invention is, therefore, to provide a blade holder in which either single or double edge blades may be held, which may be used in combination with a shaving guard and which may be attached to the end of a handle to hold a blade perpendicular to the handle, or turned and attached to the end of the handle to hold the blade extending straight outward from the handle.

Another object of the invention is to provide a clip that may be removably attached to one edge of a double edge razor blade to form a backing member therefor so that the blade may be held in a holder designed to hold single edge blades.

Another object of the invention is to provide a holder for safety razor blades by which the head of a safety razor may be turned with the blade extending straight from the handle to form a knife.

Another object of the invention is to provide a blade holder for safety razors that may be

used in combination with a guard, or that is adapted for use with the guard omitted.

Another object of the invention is to provide an attachment for razors and the like through which the device may be used as a straight razor, safety razor, scraper for paint and the like, and also in which the blade may readily be held for honing and stropping.

A further object of the invention is to provide a combination straight and safety razor which is of a simple and economical construction.

With these and other objects in view, the invention includes a handle having a threaded stud extending from one end, a blade holder in the form of a U-shaped clamp with a centrally disposed threaded socket in one side and another threaded socket in one end, a guard adapted to be positioned between the blade holder and handle, and a clip adapted to be positioned over one edge of a double edge razor blade to provide a backing therefor.

Other features and advantages of the invention will appear from the following description taken in connection with the drawings, wherein:

25 Figure 1 is a view showing a side elevation of the combination razor with the parts assembled to hold the blade perpendicular to the axis of the handle.

Figure 2 is a view showing an end elevation of the razor illustrated in Figure 1, looking toward the blade-holding end thereof.

Figure 3 is a view showing a side elevation of the combination razor with the blade mounted on the handle so that it extends straight outward from an end thereof.

Figure 4 is a detail showing the blade holder.

Figure 5 is a detail showing the guard adapted to be used in combination with the holder and blade.

Figure 6 is a view showing a clip mounted on one edge of a double edge razor blade providing a backing therefor.

Figure 7 is a view looking toward an edge of the clip with the parts sprung open or in the free positions.

Figure 8 is a modified form showing the holder with a floating safety guard mounted on extending bosses at the ends thereof.

Figure 9 is a detail showing the floating safety guard.

Referring now to the drawings, wherein like reference characters indicate corresponding parts, the combination razor of this invention includes a handle 10, a blade holder 11, a guard 12, and a clip 13.

The handle 10 may be of any suitable size or configuration, wherein it is adapted to be comfortably held in the hand for shaving, cutting and the like. At one end of the handle is a threaded stud 14 adapted to be screwed into a threaded socket 15 in the side of the holder 11 when it is desired to use the device as a safety razor, and the stud may also be screwed into a threaded socket 16 in the end of a cylinder 17 of the holder, as shown in Figure 3, when it is desired to use the device as a knife for cutting and the like, or for sharpening, honing or stropping the blade.

The cylinder 17 of the holder 11 is provided with keepers 18 and 19 arranged in spaced relation and dependently carried by said cylinder, the keepers having inwardly extending lips 20 and 21 on their ends. The lips 20 and 21 are spaced from each other so as to provide a slot 22 for frictionally holding a safety razor blade therebetween. The space intermediate the keepers 18 and 19 forms a longitudinally extending slot 23 for the reception therein of a backing element. In the design shown in Figure 1, a razor blade 24 is shown projecting below the slot 22 with a backing element 25 positioned in the slot 23.

A shaving guard 12 is illustrated in Figure 5, and this may be positioned over the blade, as illustrated in Figure 1, with clips 26 and 27 at the lower edge extending around the corners of the blade, and with a semi-circular portion 29 at the upper edge extending over the side of the cylinder 17 of the holder. The part 28 is provided with a socket 29 through which the stud 14 of the handle 10 extends, as shown in Figure 1. The lower edge of the guard is provided with a skin-stretching bar 30 and an opening 31 may be provided above the bar, the portion of the exterior of the surface of the bar 30, engaging the skin of the razor user, being smooth and straight. The edges of the bar may be provided with notches 32 and 33 to correspond with notches in the ends of razor blades. The guard 12 is particularly adapted for use with the device when it is used as a safety razor, and may be omitted when the blade is positioned so that it extends straight from the end of the handle, as shown in Figure 3, wherein the device may be used as a knife or the like.

The clip 13, illustrated in Figures 6 and 7, is provided with an outwardly extending arm 34 and projections 35 and 36 may also be provided which are positioned to correspond with notches in the edges of a safety razor blade, wherein the clip may be positioned over the upper edge of the blade, as shown in Figure 6. The clip may be placed over the upper edge of the blade and the ends held together by the thumb and forefinger, as the clip and blade are inserted in the slots 21 and 23, respectively of the holder 11.

In the design shown in Figure 8, a holder 31, similar to the holder 11, is provided with bearing bosses 38 at the ends of a cylinder 39 and a floating safety guard 40 is pivotally mounted on the bearing bosses through rings 41 and 42 at the ends thereof. The guard is formed with a bar 43 corresponding to the bar 30 of the guard 12 and in the inner surface of side bars 44 and 45 are small projections 46 and 47 which are positioned to register with notches in the ends of a blade, indicated by the numeral 48.

With the guard 40 the razor may be held in one hand and the guard may be snapped

on and off with the thumb, wherein the blade may be changed, stropped or cleaned. This guard also holds the blade in the holder, preventing lengthwise movement thereof and providing a yoke through which a strop may be placed to facilitate stropping.

The combination straight and safety razor of this invention, therefore, includes a handle, a blade holder, a guard, and a clip, wherein the blade holder may be attached by a threaded stud on the end of the handle to the handle with the guard between the holder and the handle when the holder is positioned perpendicular to the handle to form a safety razor, and, with the guard omitted, the holder may be attached through an end thereof to the end of the handle so that the blade will extend straight outward from the end of the handle, to form a knife or cutter. The blade holder is normally adapted to hold single edge razor blades, and the clip is adapted to be used over one edge of a double edge blade to take the place of the backing of a single edge blade, wherein both single and double edge blades may be held in the holder.

The parts are illustrated in their preferred form, and it will be understood that modifications may be made in the design and arrangement of the elements without departing from the spirit of the invention.

What is claimed is:

1. In a combination straight and safety razor, a razor blade holder comprising a cylinder, a pair of longitudinally extending keepers arranged in spaced relation and each having one edge dependently secured to said cylinder, a lip extending longitudinally of each of said keepers and secured to the other edge of the adjacent keeper, said lips being arranged in spaced confronting relation and cooperating with said keepers for providing a longitudinally extending slot to frictionally hold a razor blade therebetween, a bearing boss located at each end of said cylinder, and a U-shaped guard having the free ends of its legs pivotally mounted on said bearing bosses and slidably supported on said keepers, the bight of said guard constituting the skin engaging surface being smooth and straight, there being a socket in said cylinder intermediate its ends and a further socket located in the end of said cylinder and extending longitudinally inwardly thereof, and a handle having an end adapted to be received within each of said sockets and secured therein.

2. In a combination straight and safety razor, a razor blade holder comprising a cylinder, a pair of longitudinally extending keepers arranged in spaced relation and each having one edge dependently secured to said cylinder, a lip extending longitudinally of each of said keepers and secured to the other edge of the adjacent keeper, said lips being arranged in spaced confronting relation and cooperating with said keepers for providing a longitudinally extending slot to frictionally hold a razor blade therebetween, a bearing boss located at each end of said cylinder, a U-shaped guard comprising a straight longitudinal bar forming the bight of the U, a pair of legs each having one end connected to said bight, the bight of said guard constituting the skin engaging surface being smooth and straight, a ring secured longitudinally to the other end of each leg and located in a plane perpendicular to said bight for pivotal engagement with said bosses, and an in-

wardly extending projection secured to each of said legs contiguous to said one end thereof for engagement with a notch in the side edge of a safety razor blade, the legs of said guard being slidably supported on said keepers, there being a socket in said cylinder intermediate its ends and a further socket located in the end of said cylinder and extending longitudinally inwardly thereof, and a handle having an end adapted to be received within each of said sockets and secured therein.
